UNITED STATES PATENT OFFICE.

JOHN HENRY RICE, OF DALLAS, TEXAS.

VIOLIN.

1,214,075.

Specification of Letters Patent. Patented Jan. 30, 1917.

Application filed April 8, 1916. Serial No. 89,949.

To all whom it may concern:

Be it known that I, JOHN HENRY RICE, a citizen of the United States, residing at Dallas, in the county of Dallas and State of Texas, have invented a new and useful Violin, of which the following is a specification.

This invention relates to violins, one of the objects being to arrange within the body 10 of the instrument a pair of strings corresponding with two of the strings on the outside of the instrument both in the nature of the material of which they are made and in length so that when the corresponding 15 strings inside and outside of the body are placed under like tension they will produce like tones when vibrated, the interior strings constituting in addition to vibrating means, reinforces for offsetting the strains set up 20 by the tensioned outside strings, so that tendency of the belly of the body to buckle is overcome while at the same time a stronger and better tone is produced due to the sympathetic vibration of the interior 25 strings.

With the foregoing and other objects in view which will appear as the description proceeds, the invention resides in the combination and arrangement of parts and in 30 the details of construction hereinafter described and claimed, it being understood that changes in the precise embodiment of the invention herein disclosed can be made within the scope of what is claimed, without 35 departing from the spirit of the invention.

In the accompanying drawings the preferred form of the invention has been shown.

In said drawings:—Figure 1 is a central 40 longitudinal section through a violin having the present improvements combined therewith. Fig. 2 is a section on line A—B Fig. 1.

Referring to the figures by characters of 45 reference 1 designates the body of the instrument and 2 the neck, the bridge 3 being mounted on the body as ordinarily. The instrument differs from the ordinary instrument in that an additional bridge 4 is extended transversely of the cavity in the 50 body and secured to the inner surface of the belly of said body, this bridge being located adjacent the back end of said body and at a distance from the front end thereof 55 approximately equal to the distance from the bridge 3 to the neck bridge 5. Keys 6

are mounted within a bracket 7 arranged at the back end of the body and the respective keys are adapted to be engaged by E and G strings indicated generally at 8, these 6 strings corresponding with the E and G strings mounted on the bridges 3 and 5, the outside strings being indicated generally at 9. The strings 8 are preferably extended through small openings 10 in the front end 65 of the body and may be held in position by knotting the outer ends thereof. The distance between these openings and the bridge 4 will be approximately equal to the distance between the bridges 3 and 5. Thus 70 it will be seen that by turning the keys 6 until strings 8 vibrate in sympathy with the corresponding strings 9 said strings will be placed under the same tension as strings 9 and with the bridge 4, will form a truss for 75 reinforcing the belly of the body 1 thus to prevent said body from buckling under the strain to which it is subjected by the tensioned strings 9. The body is provided with the usual bass bar 11 extending between the 80 scrolls.

It has been found in practice that by providing strings 8 such as described the body of the instrument is not only rendered more durable but a better and louder tone is produced than heretofore.

While the improvements have been described as applied to a violin, it is to be understood that they can be used equally as well in connection with larger instruments 90 of the same type. Furthermore, means other than those described may be employed for holding the strings 8 in position.

What is claimed is:—

1. The combination with a violin having 95 the usual strings outside thereof, of a bridge upon the inside of the belly of the violin, strings extending longitudinally of the body and engaging the bridge and corresponding in size and length to certain of the outside strings, and means for placing said inside strings under tension whereby they will vibrate in sympathy with and produce the same tones as the corresponding outside strings.

2. The combination with a violin having 100 the usual strings outside thereof, of a bridge upon the inside of the belly of the violin, strings extending longitudinally of the body and engaging the bridge and corresponding 105 in size and length to certain of the outside strings, and means for placing said inside strings,

strings under tension whereby they will vibrate in sympathy with and produce the same tones as the corresponding outside strings, said inside strings and their bridge 5 coöperating to form a truss to reinforce the belly of the instrument.

3. The combination with a violin having the usual strings outside thereof, of a bridge upon the inside of the belly of the violin, 10 strings extending longitudinally of the body and engaging the bridge and corresponding in size and length to certain of the outside strings, and means for placing said inside strings under tension whereby they 15 will vibrate in sympathy with and produce

the same tones as the corresponding outside strings, said inside strings and their bridge coöperating to form a truss to reinforce the belly of the instrument, the distance between the bridges of the outside strings being the same as the distance between one end of the inside strings and the bridge engaged by said inside strings. 25

In testimony that I claim the foregoing as my own, I have hereto affixed my signature in the presence of two witnesses.

JOHN HENRY RICE.
